ELECTRICAL SWITCH

Robert F. Blaha, Dedham, and John D. Mayall, Attleboro, Mass., assignors to Texas Instruments Incorporated, Dallas, Tex., a corporation of Delaware

Filed May 7, 1969, Ser. No. 17,059

Term of patent 14 years

Int. Cl. D13—03

U.S. Cl. D26—13

Fig. 1.

Fig. 3.

Fig. 2.

Fig. 4.

Fig. 5.

Fig. 7.

Fig. 6.

Fig. 8.

FIG. 1 is a perspective view of a first embodiment of our new design for an electrical switch, the opposite side being a mirror image thereof.

FIG. 2 is a bottom view of the FIG. 1 embodiment.

FIG. 3 is a perspective view of a second embodiment of our new design for an electrical switch, the opposite side being a mirror image thereof.

FIG. 4 is a bottom view of the FIG. 3 embodiment.

FIG. 5 is a perspective view of a third embodiment of our new design for an electrical switch, the opposite side being a mirror image thereof.

FIG. 6 is a bottom view of the FIG. 5 embodiment.

FIG. 7 is a perspective view of a fourth embodiment of our new design for an electrical switch, the opposite side being a mirror image thereof.

FIG. 8 is a bottom view of the FIG. 7 embodiment.

We claim:

The ornamental design for an electrical switch, substantially as shown and described.
